SPRING PIN LOCK SLIDER FOR SEPARABLE
FASTENER STRINGERS

Louis H. Morin, Bronx, N. Y.

Application March 20, 1950, Serial No. 150,652

5 Claims. (Cl. 24—205.14)

1

This invention relates to what are known as sliders for use in connection with separable fastener stringers for coupling and uncoupling the stringers. More particularly, the invention deals with sliders of the spring pin lock type, wherein the lock pin, including the hinge pins, are integrally cast with the pull. Still more particularly, the invention deals with devices of this kind, wherein the separate parts of the complete slider can be assembled in simple operations of a press, thus materially reducing the cost of assembling devices of this kind.

The novel features of the invention will be best understood from the following description, when taken together with the accompanying drawing, in which certain embodiments of the invention are disclosed and, in which the separate parts are designated by suitable reference characters in each of the views and, in which:

Fig. 1 is a perspective view showing the slider and pull in spaced relationship to each other, preparatory to assemblage of the parts.

Fig. 2 is a bottom plan view of one end of the pull, prior to assemblage of a spring therewith.

Fig. 3 is a view similar to Fig. 2 showing the spring assembled.

Fig. 4 is a section on the line 4—4 of Fig. 3.

Fig. 5 is a plan view showing the assemblage of the slider and pull, illustrating one end portion only of the parts and with the pull in closed position; and

Fig. 6 is a section substantially on the line 6—6 of Fig. 5.

In devices of the kind under consideration, considerable time and effort is required in the assemblage of the parts, which results in materially adding to the cost of producing sliders having spring pin lock pulls. One of the real difficulties in this connection has been the handling and assemblage of the spring. The purpose of my invention is to simply and economically produce the slider and pull end to so construct these parts as to simplify assemblage of the spring in the pull and assemblage of the pull with the slider.

In Fig. 1 of the drawing, I have shown at 10 and 11 slider and pull parts, respectively, in spaced relationship to each other, preparatory to assemblage of these parts. The slider 10 comprises a top plate 12, bottom plate 13, joined at the wide end of the slider in a connecting web, as seen at 14, in Fig. 6 of the drawing. The top wall 12 of the slider has, at the wide end thereof, U-shaped bearing members 15, the sockets 16 of which are normally open to receive outwardly protruding integral hinge pin portions 17 on the part 11, as will clearly appear from a consideration of Figs. 1 and 5 of the drawing.

Between the bearings 15, the top wall of the

slider has a transverse groove 18 for receiving the transverse hood portion 19 of the pull 11. The wall 12 also has a longitudinally extending aperture 20 which extends into the groove portion 18 and opens into the channel 21 of the slider 10 to give access to the stringer scoops of a separable fastener, on which devices of this kind are commonly used. The stringers are not shown, as these are well-known in the art.

The aperture 20 is located adjacent one of the bearings 15 and, adjacent the other bearing 15, the wall 12 has an aperture 22 to receive one end 23 of a coil spring 24. The pull 11 is normally formed in the manner illustrated in Fig. 2 of the drawing and the rounded hood portion 19 has, at its ends, wall portions 25 and projecting side ears or tongues 26, which normally extend upwardly to give free access to the chamber or recess 27 within the hood 19. This facilitates free placement or dropping of the spring 24 into the recess between the ears or tongues 26. The pull 11 has a longitudinally extending recess 28 which opens into the recess 27 and is bordered by a raised wall or flange portion of U-shaped form, as seen at 29, and this wall or flange portion is adapted to be peened-over, as seen at 30 in Fig. 3, in securing the other end 23' of the spring 24 on the slider 11. In other words, it will be apparent that, in assembling the spring with the pull 11, the spring 24 is dropped into the recess 27 with the end 23' in the recess 28 and in a single operation, the wall or flange 29 is peened-over, as at 30, and the ears or tongues 26 are bent inwardly, in the manner illustrated in Figs. 3 and 4 to secure the spring against displacement from the recess or socket 27.

It will also appear that the hood 19 is recessed adjacent one of the walls 25, as at 31, to receive the end 23 of the spring 24 and another recess 32 is provided adjacent the other wall 25, so as to definitely define the ears or tongues 26 and facilitate their bending-over for engagement with the spring 24. The wall 25, adjacent the recess 32, has a projecting lock pin portion 33, which is adapted to pass through the aperture 20 to engage a scoop of a stringer disposed in the channel 21 of the slider 12. It will be noted from a consideration of Fig. 1 of the drawing that the wall 25 having the pin 33 thereon has an extended portion 34 for strengthening the pin 33.

After the spring 24 has been assembled with the pull, in the manner seen in Figs. 1 and 3, the spring end 23 can be swung into the dotted line position of Fig. 1, or the full line position of Fig. 3, and then the assemblage placed upon the slider 10 with the pintle bearing pins 17 in the sockets 16, after which the side walls 15' of the bearings 15 can be forced inwardly to engage the bearings

17 in the manner clearly illustrated in Fig. 5 of the drawing. Also, by appropriately positioning the pull (containing the spring in recess 27) with respect to the slider, the wall 29 may be peened over, the ears 26 bent inwardly, and the side walls 15' of the bearings 15 forced about the bearing pins 17 in one pressing stroke.

From the foregoing, it will be apparent that the slider 10 and pull 11 can be formed as die cast members with the blanks of each part, as shown in Figs. 1 and 2, and the assemblage of the spring end parts accomplished as stated before. In this way, the complete spring pin lock slider is produced very economically. The spring normally tensions the pull to maintain a locked position, thus producing an automatic lock slider and, in the operation of the slider, the pull is raised against the tension of the spring in moving the slider along the stringers to couple and uncouple the same.

Having fully described my invention what I claim as new and desire to secure by Letters Patent is:

1. A three-piece slider consisting of a slider body, a pull, and a coil spring, said pull having an enlarged portion at one end, a channel in said enlarged portion extending transversely of the pull, said channel being defined by a pair of end walls and by a pair of transversely extending side walls, the latter being substantially equal in length to the length of the channel, said end and side walls being integral with the pull, said end walls completely closing off the ends of the channel and each said end wall having an integral axle portion whose length extends only from the outer end face of each said end wall to a point spaced outwardly of an adjacent to said end face, said coil spring being disposed in the channel as the sole structure occupying said channel, said spring having one end anchored to the pull, said transversely extending sides of the channel being deformed about the spring to retain the latter in the channel, a lock element extending from one of said end walls, a pair of bearings on a wall of the slider for receiving said axle portions, each said bearing having a portion thereof deformed about the corresponding axle portion to rotatably retain the latter in the bearing, a concave recess on said slider wall extending transversely thereof between said bearings for receiving the said enlarged portion of the pull, an aperture in said slider wall for receiving said lock element, and a second aperture in said slider wall for receiving the other end of said spring.

2. In a slider of the class described, the combination of a slider body and a pull therefor, said pull having an enlarged portion at one end, a channel in said enlarged portion extending transversely of the pull, said channel being defined by a pair of end walls and by a pair of transversely extending side walls, said end and side walls being integral with the pull, said end walls closing off the ends of the channel and each said end wall having an axle portion extending outwardly therefrom, a spring in the channel as the sole structure occupying said channel, said spring having one end anchored to the pull, at least one of said transversely extending sides of the channel being deformed about the spring to retain the latter in the channel, a lock element extending from one of said end walls, a pair of bearings on a wall of the slider for receiving said axle portions, each said bearing having a portion thereof deformed about the corresponding axle portion to rotatably retain the latter in the bearing.

bearing, and means in said slider wall for anchoring the other end of said spring.

3. In a slider of the class described, the combination of a slider body and a pull therefor, said pull having an enlarged portion at one end, a channel in said enlarged portion extending transversely of the pull, said channel being defined by a pair of end walls and by a pair of transversely extending side walls, said end walls closing off the ends of the channel and each said end wall having an axle portion extending outwardly therefrom, a spring in the channel as the sole structure occupying said channel, said spring being in engagement with the pull and with the slider body, at least one of said transversely extending sides of the channel being deformed about the spring to retain the latter in the channel, a pair of bearings on a wall of the slider for receiving said axle portions, each said bearing having a portion thereof deformed about the corresponding axle portion to rotatably retain the latter in the bearing.

4. In a slider of the class described, the combination of a slider body and a pull therefor, said pull having an enlarged portion at one end, a channel in said enlarged portion extending transversely of the pull, said channel being defined by a pair of end walls and by a pair of transversely extending side walls, said end walls closing off the ends of the channel and each said end wall having an integral axle portion whose length extends only from the outer end face of each said end wall to a point spaced outwardly of and adjacent to said end face, a spring in said channel, said spring being in engagement with the pull and with the slider body, said transversely extending sides of the channel being deformed about the spring to retain the latter in the channel, a pair of bearings on a wall of the slider for receiving said axle portions, each said bearing having a portion thereof deformed about the corresponding axle portion to rotatably retain the latter in the bearing.

5. A three-piece slider consisting of a slider body, a pull, and a spring, said pull having a rounded edge portion at one end, a transverse channel in said rounded portion defined by end and side walls, said end and side walls being integral with the pull, a spring in the channel, said spring being in engagement with the pull and with the slider body, at least one of said side walls of the channel being deformed about the spring to retain the same in the channel, an axle portion extending from each said end wall, the axle portion having a length extending only from the outer end face of said end wall to a point spaced outwardly of and adjacent to said end face, a lock element on the pull adjacent one end of the channel, and a pair of bearings on a wall of the slider for receiving said axle portions.
